UNITED STATES PATENT OFFICE.

LULU B. McNAIR, OF OAKLAND, CALIFORNIA.

DESIGN FOR A CHILD'S CAPE.

Application filed August 13, 1924. Serial No. 10,445. Term of patent 3½ years.

To all whom it may concern:

Be it known that I, LULU B. McNAIR, a citizen of the United States, residing in the city of Oakland, county of Alameda, State of California, have invented a new, original, and ornamental Design for a Child's Cape, of which the following is a specification, reference being made to the accompanying drawing, forming a part thereof.

Fig. 1 is a front elevation of a child's cape, showing my new design.

Fig. 2 is a rear elevation of Fig. 1.

I claim:

The ornamental design for a child's cape, as shown.

LULU B. McNAIR.
